AMPHIBIAN LANDING DEVICE

Harry Darby and David Dahlin,
Kansas City, Kans.

Application February 17, 1944, Serial No. 522,812

4 Claims. (Cl. 9—1)

This invention relates to improvements in amphibian landing shields suitable for manual manipulation on land and in the water.

The landing of troops from barges and boats heretofore has been hazardous due to the fact that they are exposed to the gun fire of the enemy as they wade through the shallow water after leaving the barges and also as they travel across the beach.

The principal object of the present invention is to overcome these dangers to a large degree by providing an amphibian landing shield which will resist bullets, shrapnel, etc., will float in water and is also mobile on land.

Another object of this invention is the provision of a manually operable landing shield having rotatably mounted float wheels which serve to maintain the shield in partially submerged position in the water and also serve as wheels for carrying the shield when on land.

Other objects are simplicity and sturdiness of construction, efficiency and ease of operation and adaptability for use in deep or shallow water and also on land.

Reference will now be had to the drawings wherein:

Fig. 1 is a side elevation of an amphibian landing shield shown in the floating position and embodying this invention.

Fig. 2 is a side elevation of the shield shown in Fig. 1 showing its typical position when used on land.

Fig. 3 is a front elevation of the shield.

Fig. 4 is a rear elevation of the shield.

Fig. 5 is an enlarged, sectional view taken on line V—V of Fig. 4.

Fig. 6 is an enlarged, plan view of the shield partly in section.

Throughout the several views like reference characters refer to similar parts and the numeral 10 designates a substantially arcuate shield member having radially disposed spokes 12 and 13 carrying hub members 14 which are in axial alignment and adapted to receive the axle 16 on which are rotatably mounted wheel floats 18. The spoke 12 for each hub 14 is disposed in angled relation and serves to reinforce the arcuate shield to which it is welded or otherwise secured to present a light, rigid frame. The rearwardly and upwardly extending spoke 13 which extends through and beyond the arcuate shield member 10 is adapted to support a radially disposed shield sheet 26 which extends from the periphery of the arcuate shield 10. The upper edge of sheet 26 is flanged at 27 to reinforce the sheet and also to

serve to direct shrapnel, etc., away from the operators. A central hub 20 is secured in axial alignment with hubs 14 by a forwardly and upwardly extending spoke 22, and a rearwardly and upwardly extending spoke 24 which is securely welded in position. Another spoke 28 extends rearwardly from the hub 20 and serves to receive a hollow outrigger member 30 which is releasably secured thereto by pin 31. The outer extremity of member 30 carries a bifurcated member 32 which is removably secured thereto by pin 34. This member 32 is provided with bearings 36 which are adapted to receive the axle 38 of the float roller 40. It will be noted that the outrigger member extends a sufficient distance to the rear of the shield plate to serve as a stabilizer for the shield when it is in the water.

Hand grips 42 mounted on the member 30, serve as gripping means for operators when in the water and also for directing the shield when on land. When on land, it is quite possible that in many instances the outrigger float member will be removed from the shield and only the member 30 will remain intact. This member 30 will thus serve as a gripping member for manipulating the shield.

Hasps 44 carried at the rear edge of the arcuate shield member 10 are adapted to carry depending aprons 46 which normally hang downwardly by gravity but may be maintained in the raised position against member 30 by means of a latch 48. These aprons serve to protect the operator's lower extremities.

Referring to Fig. 2 where the shield is being used on land, it will be noted that apron 46 is slightly wider than the usual distance to the ground level and therefore, will rest against the ground in an inclined position, thereby preventing accidental backward movement of the shield and also will anchor the shield against backward movement due to the impact of projectiles, etc.

Port holes 50 provided with wickets 52, are conveniently positioned in sheet 26. Those portions of the shield subject to gun fire are preferably made of ballistic steel sheets while the other portions are made of relatively thin material to provide the proper buoyancy of the apparatus. All spokes, axles and other elongated members should be made of tubing closed to cause them to serve as individual floats.

The wheel floats 18 are shown as hollow drums, however, they may be made of any suitable buoyant material such as wood, cork, etc. While in the water these wheel floats are well protected

by the ballistic steel plates, however, when the device is on land, as shown in Fig. 2, projectiles might penetrate the metal of the wheels 18, since they are exposed to gun fire below the center line. This, however, would not incapacitate the device for land use, but would require repairing before they could again be used in the water. It is quite conceivable that the periphery might be made of a suitable sheet of ballistic steel. A shelf 45 normally positioned above the water line is convenient for carrying equipment, etc.

The form of landing shield shown is adapted to float in an upright position in the water and also to roll on the land to serve as a protection for the soldiers who manipulate the shield from the rear.

It is evident that many minor changes might be made in the construction of the shield without departing from the spirit of the invention.

What we claim as new and desire to be secured by Letters Patent is:

1. An amphibian landing device comprising a frame, a shield having a lower arcuate portion and an upper planar rearwardly inclined portion, buoyant wheels journaled in said frame rearwardly of the arcuate portion of said shield, an outrigger float supported by said frame and extending to the rear of said buoyant wheels whereby the device will be stabilized when floating in the water.

2. An amphibian landing device comprising a frame, a sheet metal shield supported by said frame, buoyant wheels rotatably mounted on said

frame at the rear of said shield and an outrigger carried by said frame whereby said device is stabilized to support said shield with its lower edge below the horizontal axial plane of said buoyant wheels and with its upper edge positioned above and to the rear of said wheels.

3. An amphibian landing device comprising a frame, buoyant wheels rotatably carried by said frame, a shield of sheet metal supported by said frame to extend in front of said buoyant wheels with its upper portion extending upwardly and rearwardly above said wheels whereby the device will float in water with a portion of said shield extending above the surface of the water, an outrigger carried by said frame whereby the device is stabilized in an upright floating position, and hinged sheet metal aprons carried by said metal shields adapted to contact the ground to prevent accidental backward movement of the device.

4. An amphibian landing device comprising a frame, buoyant wheels rotatably mounted on said frame, a shield member carried by said frame having a lower arcuate portion disposed substantially concentric with said buoyant wheels to extend in front thereof and having an upwardly and rearwardly inclined planar section adapted to extend to the rear of said buoyant wheels, and a buoyant drum member carried by said frame in spaced relation to said buoyant wheels whereby the shield is stabilized.
